UNITED STATES PATENT OFFICE.

CARL J. PRINZLER, OF INDIANAPOLIS, INDIANA.

DESIGN FOR A PANIC-DOOR-OPERATING BAR.

Application filed June 3, 1925. Serial No. 13,648. Term of patent 14 years.

To all whom it may concern:

Be it known that I, CARL J. PRINZLER, a citizen of the United States, residing at Indianapolis, in the county of Marion and State of Indiana, has invented a new, original, and ornamental Design for Panic-Door-Operating Bars, of which the following is a specification, reference being had to the accompanying drawing, forming a part thereof.

The drawing is a perspective view of a door operating bar showing my design.

I claim:

The ornamental design for a panic door operating bar as shown.

In witness whereof, I, CARL J. PRINZLER, have hereunto set my hand at Indianapolis, Indiana, this 1st day of June, A. D. one thousand nine hundred and twenty-five.

CARL J. PRINZLER.
